UNITED STATES PATENT OFFICE.

ROBERT CUMMING WILSON, OF ATHENS, GEORGIA.

BOTTLE-CLOSURE.

1,201,009.

Specification of Letters Patent. Patented Oct. 10, 1916.

Application filed December 13, 1915. Serial No. 66,661.

To all whom it may concern:

Be it known that I, ROBERT C. WILSON, a citizen of the United States, and a resident of Athens, in the county of Clarke and

5 State of Georgia, have invented a certain new and useful Improvement in Bottle-Closures, of which the following is a specification.

My present invention relates generally to 10 bottle closures and particularly to bottle caps or shields adapted to be associated with cork stoppers for purposes now well known, my object being to provide a cap capable of firmly gripping and retaining a 15 cork without itself entering, at any point, into the neck of the bottle in connection with which it is used.

This object I accomplish through the use 20 of a simple and inexpensive construction which is strong and durable and which provides for certain other advantages in use as hereinafter specified.

Referring now to the accompanying drawing, Figure 1 is a perspective view of the 25 most simple form of which my present construction is capable. Fig. 2 is a vertical section through a bottle neck illustrating the practical application thereto of the device shown in Fig. 1. Figs. 3 to 11 inclusive are sectional perspective views illustrating certain modifications of which my invention is capable, and Fig. 12 is a top plan view of the device illustrated in Fig. 11.

Referring now to these figures, and particularly to Figs. 1 and 2, illustrating the 30 most simple form of which my invention is capable, it will be seen that my improvements essentially include a substantially circular body plate A having a central opening 35 and a tubular upright extension B projecting upwardly from, and surrounding, said body plate opening, and in a direction therefrom relatively opposite to that of the outer depending flange C of the body plate, 40 the latter of which in use surrounds the lip D² at the upper end of the neck D' of a bottle D as seen in Fig. 2.

The tubular extension B just mentioned, 45 it will be noted, is straight from end to end and of sufficient length to firmly grip a cork E over a substantial portion thereof when inserted and forced into the opening of the body plate A in use. The cap also 50 essentially includes an outwardly flaring flange F at the upper end of the tubular extension B and which in use incloses the

upper end of the cork E as shown in Fig. 2, slightly compressed though enlarged with respect to that portion inclosed by the extension B.

Thus in use, it being understood that a 55 cork of substantially increased diameter with respect to the diameter of the body opening and the neck or tubular portion B is utilized, the cork upon being forced through the body opening until its outer end is substantially flush with the outer end of flange F, is compressed and firmly gripped by the extension B throughout the length of the latter and is formed with shoulders E' 60 and E² above and below the extension B, the former being located within the flaring flange F and the latter being located at the relatively opposite side of the body plate A, so that in the after use of the cap in 65 connection with the cork all danger of the cork pulling from the cap in one direction or the other, is entirely eliminated.

In this connection it is desired to call attention to the fact that, due to the peculiar 70 texture of cork commonly used as a bottle stopper, it is necessary to grip the surface of the cork firmly and at more than a single point and that shouldered portions of the cork must be left upon the relatively opposite sides of its portion gripped in order 75 that the cork may be forced into the bottle neck and removed therefrom by grasping the bottle cap of the nature I have shown. For this purpose the inner surfaces of the 80 extension B and flange F are sufficient if smooth, but it may be desirable to roughen these inner surfaces as shown in Figs. 3, 4, 5, 11, and 12, in order to more firmly grip the cork, and it may be desirable to either 85 provide the flange F with an internal rib F' at its outer end as shown in Fig. 6 to engage the upper end of the cork, or to serrate the flange as indicated at F² in Fig. 7, providing tongues which may be pressed 90 into the material of the cork.

In the form shown in Fig. 6, and constructed as just above described, the cork is to be pushed beyond the internal rib F' and permitted to expand inside of the same 95 and closely against the inner surface of the flange F to prevent upward movement of the cork with respect to the cap when, for instance, the cork is thrust into the neck of a bottle. Furthermore, in connection with 100 the serrated flange as indicated at F² in Fig. 7 just above mentioned, the cork may

be allowed to swell or bulge outwardly between the several tongues, without thrusting the latter into the material of the cork.

In Fig. 4 the extension B is shown with an internal circumferential rib B', this construction being reversed in Fig. 5, wherein the extension B has an outwardly presented circumferential rib forming an inner circumferential groove B². The extension B may however be provided with inwardly indented projections B³ as shown in Fig. 3, spaced apart to enter the material of the cork, and the flange F may be similarly constructed with inwardly indented portions F³ as shown in Fig. 10. The flange F may be also provided, for the same purpose, with inset integral tongues F⁴ as shown in Fig. 11.

In the use of a bottle cap of this type, as well known, a label is pasted across the top of the cork E, covering the upper edge of the flange F in the present construction, as shown in the figures just described. The upper edge of the flange F may, however, have a surrounding straight extension F⁵ as shown in Fig. 9, and the body plate A may have its central portion inset as indicated at A' in Fig. 8, so as to bring the outer upper edge of the flange F in the same horizontal plane with the outer portion of the body plate A, thus providing for a label to cover the entire upper surface of the cap.

The several modified constructions hereinbefore described for the purpose of promoting increased gripping action between the cap and the cork, may be utilized either separately as indicated in Figs. 4, 5, 6, 7, and 10, or may be utilized together as in Fig. 11 where, in addition to the inset tongues F⁴ of the flange F, the extension B is provided with inner projections B⁴ similar to those shown in Fig. 3.

Furthermore, in carrying forward the same idea of additional gripping action upon the cork, the opening of the body plate A and the tubular extension B as well as the flaring flange F may be of oval form instead of perfectly round, so as to compress the cork greater in one direction than in the other, as shown in Fig. 12, this figure being a plan view of the form in Fig. 11.

It will thus be seen that in addition to the fact that I obviate all danger of accidental displacement of the cork with respect to the cap being used, I provide according to the foregoing object, a cap engageable with a cork without itself entering, at any point,

into the bottle or its neck in connection with which the cap and the cork are utilized.

I claim:

1. A bottle closure consisting of a body plate having a central opening through which a cork may be partly extended, said cap being provided with an outer extension surrounding its said opening and consisting of a straight wall whereby to evenly and firmly grip the cork along a substantial portion of its surface adjacent its outer end, said extension having an outwardly flaring flange at its outer end in which the outer end of the cork is received. 60

2. A bottle closure consisting of a body plate having a surrounding flange at its edge and having a central opening through which a cork may be partly extended, said cap being provided with an extension surrounding its said opening and projecting therefrom in a direction opposite to that of the body plate flange, said extension consisting of a straight wall whereby to evenly and firmly grip the cork along a substantial portion of its surface adjacent its outer end, said extension having an outwardly flaring flange at its outer end in which the outer end of the cork is received. 75

3. A bottle closure consisting of a body plate having a central opening and an extension surrounding and projecting outwardly from said opening, said extension consisting of a straight wall and having an outwardly flaring flange at its outer end to receive the outer end of a cork forced into the said extension, said extension having a roughened inner cork gripping surface. 85

4. A bottle closure consisting of a body plate having a central opening and an extension surrounding and projecting outwardly from said opening, said extension consisting of a straight wall and having an outwardly flaring flange at its outer end to receive the outer end of a cork forced into the extension, said flange having a roughened inner cork gripping surface. 95

5. A bottle closure consisting of a body plate having a central opening and an extension surrounding and projecting outwardly from said opening, said extension consisting of a straight wall and having an outwardly flaring flange at its outer end to receive the outer end of a cork forced into the extension, said extension and flange being shaped to more tightly grip the cork in one direction than the other. 105

ROBERT CUMMING WILSON.
